United States Patent Office

Des. 221,833
Patented Sept. 14, 1971

221,833

CASTER WHEEL

Raymond S. Haydock, deceased, late of Chicago, Ill., by
Mildred Rose Haydock, executrix, Chicago, Ill. (8020
N. Austin Ave., Morton Grove, Ill. 60053)

Filed Mar. 18, 1969, Ser. No. 16,316

Term of patent 14 years

Int. Cl. D8—04

U.S. Cl. D8—226

Fig. 1.

Fig. 2.

FIG. 1 is a side elevational view of the caster wheel embodying the features of the present invention;

FIG. 2 is an edge elevational view of the caster wheel;

FIG. 3 is a perspective view of the two parts of the caster wheel, separated from each other; and

FIG. 4 is a sectional view of the caster wheel proper, without the tire.

I claim:

The ornamental design for a caster wheel, as shown.
